US0D1063191S

(12) **United States Design Patent** (10) **Patent No.:** **US D1,063,191 S**
(45) **Date of Patent:** **** Feb. 18, 2025**

(54) **CASE**

(71) Applicant: **JUUL Labs, Inc.**, San Francisco, CA (US)

(72) Inventors: **Brandon Cheung**, San Francisco, CA (US); **Carlos A. Dominguez**, San Pablo, CA (US); **Matthew J. Malone**, Los Angeles, CA (US); **John Travis Wettrath**, San Francisco, CA (US)

(73) Assignee: **JUUL Labs, Inc.**, Washington, DC (US)

(**) Term: **15 Years**

(21) Appl. No.: **29/870,764**

(22) Filed: **Feb. 3, 2023**

(51) **LOC (15) Cl.** **27-06**

(52) **U.S. Cl.**

USPC **D27/189**

(58) **Field of Classification Search**

USPC D27/100, 101, 162, 163–169, 172, D27/183–194; D9/643, 648, 756;

D3/273, 274, 283, 289, 290, 294, 301

CPC A24F 47/00; A24F 47/002; A24F 47/004;

A24F 47/006; A24F 47/008; A24F 15/01;

A24F 15/015; A24F 13/00; A24F 15/00;

(57) **CLAIM**

The ornamental design for a case, as shown and described.

DESCRIPTION

FIG. 1 is a top, front, and right side perspective view of a case showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The dash-dash broken lines illustrate portions of the case that form no part of the claimed design.

1 Claim, 4 Drawing Sheets
